(57) **CLAIM**

The ornamental design for a histologic shelf container for biological samples, as shown and described.

DESCRIPTION

FIG. 1 is a top, right, and rear sectional perspective view of a histologic shelf container for biological samples taken from line 1-1 in FIG. 6 showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is bottom view thereof; and,

FIG. 8 is a sectional view thereof, taken from line 8-8 in FIG. 2.

The broken lines in the drawings depict portions of the histologic shelf container for biological samples that form no part of the claimed design. The dot-dash lines in the

(Continued)

drawings depict symbolic break lines. Any portions of the article between the break lines form no part of the claimed design.

1 Claim, 8 Drawing Sheets
